Application October 1, 1943, Serial No. 504,552

11 Claims. (Cl. 123—176)

Our invention relates to internal combustion engines, and more particularly to the cooling of pistons in a compression ignition or Diesel engine.

In a compression ignition engine, the pistons are usually of odd shape, and the heat of combustion is not, generally, immediately uniformly distributed in the main combustion chamber of the engine, as is the case with respect to a spark ignition internal combustion engine. Therefore, to minimize hot spots and provide for adequate cooling, it is desirable to cool the pistons by a cooling fluid, such as the oil employed in lubrication of the engine. Such cooling of the pistons also enables the wall thicknesses at areas at which heat is concentrated by injection of fuel thereagainst, to be made thinner than would otherwise be the case, thus permitting reduction in weight which is an important factor.

Objects of our invention, among others, are the provision of an improved piston cooling arrangement wherein cooling fluid is continuously supplied against the piston independent of inertia effects that would occur by having passages for the cooling fluid in the connecting rod for the piston; which is particularly adapted for employment with an engine of the radial type, especially a radial compression ignition engine; and which is of a relatively simple construction. Other objects of our invention will become apparent from a perusal of the following description thereof.

Referring to the drawings:

Fig. 1 is a fragmentary, partially schematic, end view of a form of radial internal combustion engine embodying the arrangement of our invention; the direction of the view being indicated by arrow 1 in Figs. 2 and 7.

Fig. 2 is an enlarged fragmentary section, partially schematic, taken in planes indicated by line 2—2 in Fig. 1.

Fig. 3 is a sectional elevational view, also partially schematic, taken in a plane indicated by line 3—3 in Fig. 2.

Fig. 4 is an enlarged fragmentary section taken in a plane indicated by line 4—4 in Fig. 3.

Fig. 5 is an enlarged fragmentary section taken in a plane indicated by line 5—5 in Fig. 2.

Fig. 6 is an enlarged fragmentary section taken in a plane indicated by line 6—6 in Fig. 1.

Fig. 7 is an enlarged sectional view, looking in the same direction as Fig. 2, illustrating additional parts on the engine but taken in planes different from the planes of Fig. 2, as is indicated by line 7—7 in Figs. 1 and 3.

Fig. 8 is a fragmentary section taken in a plane indicated by line 8—8 in Fig. 7.

The engine illustrated is a radial Diesel or compression ignition engine of the type disclosed in our assignee's copending application by Lloyd E. Johnson and Carl R. Maxwell, Serial No. 499,892, filed August 25, 1943. However, it is to be understood that the features of our invention, although particularly adapted for a compression ignition engine, may be employed in other types of internal combustion engines. As illustrated, the engine includes annular crankcase member 2 having peripherally disposed air-cooled cylinders 3 detachably mounted thereon. Air-cooled heads 4 are detachably connected to the outer ends of the cylinders; and on each of such heads is mounted an air-cooled auxiliary combustion chamber 6 in the form of a pre-combustion chamber, and in which is seated fuel injection nozzle 7 connected to a fuel injection pump 8 by fuel line 9.

A combustible fuel mixture is ejected from auxiliary combustion chamber 6 into main combustion chamber 11 of each cylinder through orifices 12 formed in the inner end of each pre-combustion chamber. As can be noted from Figs. 3 and 7, the crown of working piston 13 in each cylinder is of an odd shape, in that it is not symmetrical about a center point; and combustible fuel is introduced into the main combustion chamber 11 off-center with respect to the center of the crown. As a result, the crown of the piston would ordinarily have a hot spot which the cooling system of our invention is designed to obviate as will be described hereinafter.

As is usual in radial engines, one of the pistons is connected to a master connecting rod 14 connected to crankshaft 16 of the engine; while the other pistons are connected in the usual manner to connecting, link rods 17. With reference to Figs. 3 and 7, each rod is connected to an associated piston, by means of a wrist pin 18 secured in spaced bosses 19 integral with the inner side 20 of the crown of the associated piston 13. Preferably, the inside wall of the piston is grooved at 21 to provide cooling fins.

Detachable connected to an end of crankcase 2 is a nosepiece member 22 on which fuel injection pumps 8 are supported, and which also supports reciprocatable valve tappet followers 23 for actuating valves 24 through suitable push rods 26, only a portion of which appear in Fig. 7. For distributing lubricant to various parts of the engine that have to be lubricated, including valve 55 tappet followers 23, an annular interior manifold

passage 27 is formed in nosepiece 22, to which are connected feed passages 28, in the nosepiece, leading to some engine parts to be lubricated. Preferably, manifold passage 27 is formed in the face of nosepiece 22 adapted to be clamped against a complementary face on crankcase 2, and is open to such face; a sealing ring 29 of suitable resilient sealing material, such as rubber, being clamped between nosepiece 22 and crankcase 2 to seal off manifold passage 27.

Lubricant is conducted to manifold passage 27, by a passageway 31 formed in nosepiece 22, and which is connected to an exterior conduit or piping 32, by threaded coupling or fitting 33 of any suitable construction. Such piping 32 is bent, as is illustrated in Fig. 1, and is also connected to a means of lubricant supply, by a suitable elbow coupling or fitting 34 in turn screwed in a coupling elbow 36 which is connected to an annular-like oil distributing manifold conduit or piping 37 mounted on nosepiece 22, exteriorly of the engine or without crankcase 2. Brackets 38, detachably secured to the nosepiece adjacent one end and fastened to exterior manifold 37 by suitable means such as welding, provide the support for manifold 37 on the engine. Manifold 37 not only provides a means for supplying oil to interior manifold 27, but also provides a means for distributing lubricant for cooling of the pistons, in a manner to be described.

A continuous supply of lubricating oil is conducted to manifold 31, as long as the engine is running, by a suitable lubricant supply pump (not shown), commonly employed in an engine of the type described, for force feeding of lubricant. Such pump feeds the lubricant at a pressure of about 80 pounds per square inch, to a supply pipe 39 connected therewith, and to the coupling elbow 36 by fitting 41. The described pressure is desired in the particular engine in which our installation is now employed because some of the engine parts are best lubricated at this pressure. However, in such engine, it is desirable that the pressure of the oil in manifold 37, which is also employed to cool the pistons, be at a lesser pressure. For this reason, we preferably provide in coupling elbow 36 adjacent supply pipe 39, a ring member 42 having a pressure reducing orifice 43 of a size designed to reduce the pressure to about 40 pounds per square inch.

Associated with each cylinder of the engine is a conduit or piping 44 connected to manifold 37, and which provides a feed line for directing oil against the inner side 28 of the piston crown to cool the same. As can be seen more clearly from Fig. 2, each of feed lines 44 is connected at one end to manifold 37, by a suitable coupling or fitting 45, and is bent exteriorly of the engine to enable projection or extension thereof through the crankcase rim or peripheral wall 46. The inner portion 47 of each feed line 44, which provides a jet part, is bent outwardly so as to extend a short distance beyond the inner end portion 47' of the associated cylinder 3, to direct a jet 48 of the cooling oil against inner side 28 of the piston crown.

This jet is created by means of a tip member 49 fixed in the discharge end of jet part 47 by suitable means, such as welding 51, and having a jet-type discharge outlet orifice 52, which directs the cooling oil in a substantially solid unbroken stream or jet (in contradistinction to a spray) at a predetermined location on the inner side 28 of the piston crown. It is desirable that the cooling oil be introduced against the piston in

the manner described, and not in the form of a diffused spray, because this enables the volume of oil directed against the piston to have the maximum cooling effect because the entire quantity of injected oil will wash against inner side 28 of the piston crown. A spray which will diffuse, will not perform this function because some of the cooling oil will hit the peripheral wall of the piston and also the cylinder wall. In this connection, jet 48 is directed at the location on piston crown adjacent which the combustible fluid is introduced from auxiliary combustion chamber 6, to provide quick dissipation of heat from such portion of the piston crown at which the highest temperatures tend to occur.

To provide for proper directing of cooling oil jet 48, means is provided for fixedly securing or holding piping 44 to crankcase 2, and to hold jet part 47 thereof against turning. For this purpose, piping 44 is formed essentially, in two parts, namely the outwardly bent jet part 47, and an inlet part 54. Jet part 47 is formed with a flange or shoulder 56 adapted to engage the inner side of crankcase rim 46, and with a screw-threaded portion 57 which projects exteriorly of the rim; jam or lock nuts 58 being screwed on portion 57 to clamp jet part 47 to the crankcase. For precluding angular turning of such jet part, a locking pin 59 is inserted in a groove, a part of which is formed in the wall of jet part 47 and another part of which is formed in the adjacent wall surface of the crankcase rim 46. Inlet part 54 is detachably connected to screw-threaded portion 57 of jet part 47, by a suitable coupling or fitting 61.

From the preceding, it is seen that piping, independent of any conduit passage formed in a connecting rod or link, is provided for introducing the cooling oil against the piston crown. This is important in insuring a steady continuous flow of cooling oil while the engine is running, which might not otherwise be the case were a conduit passage drilled in the connecting rod or link to conduct the cooling oil against the piston crown, because in the latter case the flow of oil would be effected by inertia effects imparted to the connecting rod or link as it reciprocates. Also, with the arrangement of our invention, the flow of oil is independent of crankshaft bearing pressure which is not the case where the oil is conducted through a passage in the connecting rod.

In addition, the independent piping is advantageous in a radial type of engine, wherein it is difficult to form an adequate manifold adjacent the crankshaft for conducting the oil to passages in the connecting rods or links, because of the limited space in such an engine. Another important factor of the arrangement of our invention, which makes for compactness, lies in the fact that exterior manifold 37 provides not only a distributing source for the feed lines directing the cooling oil against the pistons, but also for the feed line which is connected to interior manifold 27 which is utilized to conduct lubricating oil to other engine parts to be lubricated.

We claim:

1. In a radial internal combustion engine; a piston cooling system comprising an annular-like manifold for cooling fluid, and feed lines connected to the manifold for directing the cooling fluid to the pistons.

2. In an internal combustion engine including a member having cylinders and pistons within

such cylinders; a piston cooling system including a manifold for cooling fluid and which is mounted without said member, and feed lines connected to the manifold and extending into said member for directing the cooling fluid to the pistons.

3. In an internal combustion engine including a member having cylinders and pistons within such cylinders; a piston cooling system including a manifold pipe for cooling fluid and which is mounted without said member, feed lines connected to said manifold and extending into said member for directing the cooling fluid to the pistons, and means for fixedly securing said lines to said member.

4. In an internal combustion engine including a member having cylinders and pistons within such cylinders; a piston cooling system including a manifold for receiving oil, feed lines connected to said manifold for directing the oil to the pistons, a second manifold for oil to be conducted to other engine parts to be lubricated, and a line for conducting oil from said first mentioned manifold to said second manifold.

5. In a radial internal combustion engine having a crankcase member, a plurality of cylinders disposed about the crankcase member, and pistons within the cylinders; a piston oil cooling system comprising an annular-like manifold pipe for oil and which is mounted on the engine without the crankcase member, feed lines connected to the manifold each having a portion extending into the crankcase member and having an outlet for directing oil against an associated piston, and means fixedly holding each of said feed lines on the crankcase member.

6. In a radial internal combustion engine having a crankcase member, a plurality of cylinders disposed about the crankcase member, and pistons within the cylinders; a piston oil cooling system comprising an annular-like manifold pipe for oil and which is mounted on the engine without the crankcase member, feed lines connected to the manifold each having a portion bent to extend into the crankcase member and having an outlet for directing oil against an associated piston, and means fixedly holding each of said feed lines on the crankcase member against turning with respect thereto.

7. In a radial internal combustion engine having a crankcase member, a plurality of cylinders disposed about the crankcase member, and pistons within the cylinders; a piston oil cooling system comprising an annular-like manifold pipe for oil and which is mounted on the engine without the crankcase member, feed lines connected to the manifold each having a portion extending into the crankcase member and having an outlet for directing oil against an associated piston, an interior manifold for oil to be conducted to other engine parts to be lubricated, and a line for conducting oil from said first mentioned manifold to said interior manifold.

8. In a radial internal combustion engine having a crankcase member, a nosepiece member

adjacent the crankcase member, a plurality of cylinders disposed about the crankcase member and having their inner ends communicating with the inside of the crankcase member, and pistons within the cylinders; a piston oil cooling system comprising an exterior annular-like manifold pipe for oil, brackets secured to the nosepiece member for supporting such manifold, and feed lines connected to the manifold each having a portion extending into the crankcase member for directing oil against an associated piston.

9. In a radial internal combustion engine having a crankcase member, a nosepiece member adjacent the crankcase member, a plurality of cylinders disposed about the crankcase member and having their inner ends communicating with the inside of the crankcase member, and pistons within the cylinders; a piston oil cooling system comprising an exterior annular-like manifold pipe for oil, brackets secured to the nosepiece member for supporting such manifold, and feed lines connected to the manifold each having a portion extending into the crankcase member for directing oil against an associated piston, one of said members having an interior manifold passage for oil to be conducted to other engine parts to be lubricated, and a line including a passage portion in the nosepiece member for conducting oil from said first mentioned manifold to said interior manifold.

10. A compression ignition or the like engine having a cylinder, a piston within the cylinder, means for introducing combustible fuel into the cylinder adjacent a portion of the piston crown, means for cooling the piston comprising a conduit member for continuously directing cooling fluid against the piston crown adjacent the portion thereof at which fuel is introduced, said conduit means being adjacent the wall portion of the cylinder and independent of the connecting rod and wrist pin, and a jet-type discharge orifice mounted in the conduit means within the cylinder to direct the cooling fluid in a substantially unbroken stream against the piston.

11. A compression ignition or the like engine having a cylinder, a piston within the cylinder, means for introducing combustible fuel into the cylinder adjacent a portion of the piston crown, means for cooling the piston comprising a conduit member for continuously directing cooling fluid against the piston crown adjacent the portion thereof at which fuel is introduced, said conduit means being adjacent the wall portion of the cylinder and independent of the connecting rod and wrist pin, a jet-type discharge orifice mounted in the conduit means within the cylinder to direct the cooling fluid in a substantially unbroken stream against the piston, and means between the discharge orifice and the conduit means to hold the discharge orifice against rotation in the conduit means.
